(57) **CLAIM**

The ornamental design for an automatic guided vehicle, as shown and described.

DESCRIPTION

FIG. 1 is a perspective view of an automatic guided vehicle showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is another rear view thereof, shown in environmental use, wherein an object to be conveyed is disposed on the present design on a walking surface.

A bottom view of the present design is omitted since it does not contain ornamental features. The dash lines in FIG. 8 represent the object to be conveyed and the walking surface that are the environments only and form no part of the claimed design.
